JULIUS H. LUTZ, OF NEW YORK, N. Y.

SUCTION ELEMENT AND SUCTION VENTILATOR FOR AUTOMOBILES.

Application filed October 26, 1923. Serial No. 670,895.

This invention relates to improvements in suction elements and suction ventilators for automobiles.

One of the objects of this invention is to utilize the moving exhaust gases of an engine, and particularly the exhaust gases of an automobile explosive engine for the purpose of inducing a suction of air in a suction element which may be utilized for the ventilation of the closed bodies of cars driven by such explosive engines.

Another object of my invention is to produce a ventilator for closed automobile bodies which may be operated to draw or suck air from the interior of the car body by means of air-suction induced by the movement of the exhaust gases from the engine and without in any way affecting, consuming or reducing the normal power of the engine.

Another object of my invention is to produce a ventilating device which may be readily attached to the exhaust pipe of an automobile and which may be installed in a car body without the necessity of building in.

Another object of my invention is to produce a ventilator of the type specified in which the air-suction induced in a conduit or channel by the movement of the exhaust gases from the engine will automatically open a valve to permit the suction through such conduit of air from the interior of the closed car, and which valve will be normally retained in closed position to prevent the entrance or reverse movement of air or gases through said ventilator conduit or channel.

Another object of my invention is to provide a suction element for ventilators in combination with a flexible conduit communicating with a ventilator opening or grating in one of the walls of a closed car, whereby a connection may be made with said suction element and one or more ventilating openings or gratings positioned at varying points within the car.

With these and other objects in view, the invention comprises the combination of members and arrangement of parts so combined as to co-act and cooperate with each other in the performance of the functions and the accomplishment of the results herein contemplated, and comprises in one of its adaptations the species or preferred form illustrated in the accompanying drawings, in which:

Fig. 1 is a side elevation of an automobile

showing an installation of my improved ventilating apparatus with my suction element positioned at the end of the exhaust pipe;

Fig. 2 is a longitudinal section through such apparatus including a ventilator grating and conduit, a flexible riser conduit, a suction element operated by the movement of the exhaust gases of the automobile engine and a spring-pressed valve normally retained in closed position but operable to open by the suction of said suction element;

Fig. 3 is a front view of the ventilating grating, shutter and conduit preferably included within improved apparatus; and

Fig. 4 is a view in side elevation of an engine exhaust showing in section my suction element attached intermediate the ends of the exhaust pipe.

Referring now to these drawings, which illustrate a preferred embodiment of my invention, 1 indicates a closed automobile, the interior 1^a of which it is desired to ventilate, said automobile being provided with the usual explosive engine 2 having an exhaust conduit or pipe 3.

In the preferred embodiment of my invention I provide a suction element 4 which is, as illustrated, connected to the terminal of the exhaust pipe 3 at the rear of the muffler 5 in such a manner as to be operable by the movement or flow of gases through the said exhaust conduit or pipe 3 to create in the body-portion 4^a of said element 4 a suction which may be applied or communicated in any suitable manner to the interior compartment 1^a of the said closed car 1. In the preferred form illustrated in Figs. 1 and 2, the suction element 4 is mounted at the terminal end of the exhaust pipe and has a connection, as shown, by means of a flexible tube 6 with a ventilating opening adjacent to the top of one of the walls of the car. Any suitable form of ventilating device may be used, as for example, a simple grating or it may, as shown, comprise a grating member 7 provided with openings 8 wholly or partially closable by means of a shutter or cover 9 which, as shown, is operated to close over the grating openings by a button or knurled knob 10.

In the preferred form shown, a ventilating opening 11 is made in the lining of one wall of the car body and a flattened ventilator conduit 12 is placed in registration

with the inner side thereof, while a grating 7 and shutter 9 are connected thereto from the outside by means of screws 7^a or like fastening devices, and the ventilator conduit is connected by suitable connections 13 and a flexible tube 6 to the suction element. In the preferred form shown, however, I preferably interpose in the path of the suction and between the ventilator grating and suction element a valve 14 operable to open by the suction created in the suction element and being normally closed and retained in closed position by means of a spring 15.

15 In the form shown in Fig. 4, the suction element which is in all respects similar to the element shown in Fig. 2, is interposed in the conduit close to the engine and at the opposite side of the muffler 5 so as to procure the benefit of the more rapid movement of the gases before the same reach the muffler and are retarded thereby. In other respects the construction is similar to that described and shown in Figs. 1 and 2.

20 25 The construction of the suction element in both cases is similar. Each of such suction elements, as shown, comprises a shell or casing 4 having an enlarged body portion 4^a and a contracted suction channel 4^b preferably surrounding the periphery of the gas-ejecting end of the exhaust pipe or conduit 3 and communicating with the flowing stream of gases passing through and being ejected from the end of the conduit or exhaust pipe, so that the outward movement of the exhaust gases will induce a movement through the channel from the enlarged body

portion of the suction element and thus cause or create a suction in the conduits to which said suction element is connected.

40 In the embodiment shown in Fig. 2 it will be obvious that so soon as a suction is created within the valve casing 16, the valve 14 will be sucked downwardly against the action of the spring so as to open the 45 channel and permit the suction of air through the seat and flexible tube from and through the ventilating device to the interior of the car 1.

Having described my invention, I 50 claim:

The combination with an automobile having an engine from which leads an exhaust conduit, and a body compartment independent of and removed from the engine, of a 55 suction element having a suction channel communicating with the exhaust conduit whereby the moving exhaust gases induces a suction of air through said suction element, a ventilating element mounted in the wall lining of said body compartment and having variable openings communicating with the interior of said body compartment, a conduit connecting said suction element with said ventilating element and a valve interposed between said suction element and said ventilating element, said valve being normally retained in closed position but operable to open said induced air suction to 60 ventilate the body compartment.

65 70 In witness whereof, I have signed my name to the foregoing specification.

JULIUS H. LUTZ.
